UNITED STATES PATENT OFFICE.

FRED J. RYNERSON, OF SAN DIEGO, CALIFORNIA.

LADDER FOOT.

1,417,353.

Specification of Letters Patent. Patented May 23, 1922.

Application filed October 11, 1919. Serial No. 329,398.

To all whom it may concern:

Be it known that I, FRED J. RYNERSON, a citizen of the United States, residing at San Diego, in the county of San Diego and State 5 of California, have invented new and useful Improvements in Ladder Feet, of which the following is a specification.

This invention relates to attachments for ladders and has for an object the provision 10 of an attachment which may be secured to the lower end of the legs of a ladder to prevent the same from slipping or marring the surface upon which the ladder may rest.

Another object is the provision of a device 15 of this character which will adjust itself to uneven surfaces and to the inclination at which the ladder may be placed, at the same time maintaining a firm and even contact with said surface.

20 A still further object is the provision of means by which the supporting feet which are included in the invention, may be changed, so as to adapt them to various places or positions.

25 Other objects and advantages of the invention will appear as the following description is read in connection with the accompanying drawings.

In the drawings:

30 Figure 1 is a front elevation of the lower portion of the ladder showing my device applied thereto. Figure 2 is an elevation taken at right angles to Figure 1 on a larger scale and showing the ladder foot device. 35 Figure 3 is an enlarged longitudinal sectional view on the line 3—3 of Figure 1 and, Figure 4 is a fragmentary detail view of a portion of the foot.

Referring more particularly to the drawings the numeral 14 designates the sides of 40 a ladder upon which my non-slipping foot is designed to be engaged. In carrying out my invention I provide a foot structure which includes a socket member formed as 45 a pair of plates 29 spaced apart and connected at one edge by a web, these plates being designed to be engaged upon opposite sides of each foot or side 14 of the ladder. The plates 29 are formed with holes 13 for 50 the passage of suitable screws or other securing members whereby to be secured upon the ladder. At the lower edges the plate members 29 are formed substantially centrally with reduced extensions 30 which are 55 of somewhat spherical hollow formation and which are provided at their edges with re-

cesses 31. The numeral 18 designates the foot proper which includes a block or base portion 32 upon the lower side of which is suitably secured a tread member 33 which 60 may be formed of rubber which is preferably corrugated or toothed whereby to provide a non-slipping surface. The upper portion of the base or block 32 is formed with a concavity 34 receiving the partially 65 spherical projections 30 and the base or block 32 is furthermore formed with a central recess 37 which receives a stem 35 which is formed on a half ball 36 which is engaged within the mating partially spherical members 30 of the plates 29.

From this construction it will be seen that when the plates 29 are secured upon the sides of a ladder with the semi-balls 36 engaged in position within the mating socket 75 members 30 and the stem 35 engaged within the recess 37 the ladder will have free movement with respect to the feet members 18 while at the same time slipping of the ladder upon any surface upon which it is disposed will be prevented. It is highly desirable to provide a set screw 38 which is 80 screwed into the base 32 and which engages the stem 35 whereby to prevent disengagement of the foot member 18 from the plates 85 29 when the latter are secured upon the sides of the ladder.

From the foregoing description and a study of the drawings it will be readily apparent that I have thus provided a simply 90 constructed and consequently inexpensive foot attachment for ladders which will efficiently operate to prevent slipping of the ladder regardless of the surface upon which it is supported. Owing to the simplicity of 95 the construction and the fewness of the parts it is apparent that there is practically nothing to get out of order and that the device should consequently have a long life and satisfactorily perform all the functions 100 for which it is intended.

While I have shown and described the preferred embodiment of the invention it is of course to be understood that I reserve the right to make such changes in the form, 105 construction and arrangement of parts as will not depart from the spirit of the invention or the scope of the subjoined claim.

Having thus described my invention I claim:

A ladder foot comprising a pair of plates secured upon opposite sides of each leg of a

ladder, said plates having their lower ends formed with extensions of concavo-convex form mating to define a substantially hemispherical socket, a block associated with each 5 pair of plates and formed in its upper face with a partially spherical concavity receiving the assembled socket members, the block

being further formed with a bore leading into the concavity and a half-ball member fitting within said socket and having a stem 10 secured within said bore.

In testimony whereof I affix my signature.

FRED J. RYNERSON.
